 United Shoe Machinery Corporation, Flemington, N. J., a corporation of New Jersey

Application February 4, 1941, Serial No. 377,345

5 Claims. (Cl. 164—21)

This invention relates to presses and is herein illustrated as embodied in a clicking machine for dieing out blanks from sheet material.

Machines of this type commonly comprise a cutting bed, a vertically movable post, and an arm or beam secured to the post and movable over the cutting bed about the axis of the post, means being provided for reciprocating the post and the beam to cause the beam to apply pressure to a die placed in a selected position on a piece of sheet material supported on the cutting bed, and thereby to force the die through the sheet material, such as leather, to cut out a blank.

It is an object of the invention to provide an improved clicking machine which shall operate smoothly and effectively with the expenditure of but little power and which may be easily started irrespective of the angular position of the arm.

In accordance with a feature of the invention, the arm or beam referred to above is immovable vertically and supports a presser member of relatively small size, as compared with the arm, the presser member being caused to move downwardly with relation to the arm upon initiation of the power operation of the machine to apply pressure to the die. The power operation of the machine is initiated by means of a manually operable mechanism, one part of which is mounted on the horizontally swingable arm and another part of which is mounted on the machine frame. The connecting means between these two parts of the manually operable initiating mechanism is disposed substantially in alignment with the axis of rotation of the arm, so that the power operation of the machine may be initiated with ease in any angular position of the arm. Moreover, the illustrated machine is provided with power-actuated mechanism for reciprocating the presser member, and similarly one part of this mechanism is mounted in the machine frame and another part in the abovementioned arm supporting the presser member. The arrangement is such that the connecting means between these two parts of the power-actuating mechanism is disposed in alignment with the axis of rotation of the arm, so that the presser member may be reciprocated in any desired angular position of the arm.

Other objects of the invention and features of construction will be apparent from the following description and will be pointed out in the claims.

In the drawings,

Fig. 1 is a view in side elevation of a clicking machine illustrating a preferred embodiment of the invention;

Fig. 2 is a sectional view of the machine taken on the line II—II of Fig. 1; and

Fig. 3 is an end view of the presser member and its support with certain parts broken away.

Referring to Fig. 1, the illustrated clicking machine comprises a C-shaped frame 10 containing bearings 12 and 14 for a casting 16 of generally U-shaped cross section and supporting at its lower end a cutting bed 18 adjustable vertically by means not shown. The casting 16 is rotatable about a substantially vertical axis and is provided at its upper and lower extremities with pivotal extensions 11 and 13 seated in the bearings 12 and 14. To facilitate the removal of the casting 16 from the machine, the upper bearing 14 is semi-circular and has secured to it a correspondingly shaped removable bearing portion 20. On top of the bearing portions 14 and 20 is provided a roller thrust bearing 22 held in place by a collar 24, surrounding the upper extension 13 of the casting 16 and bearing a cap plate 26 secured to the upper end face of the casting 16 by means of screws 28.

The casting 16 carries a supporting arm 30 for a presser member 31 in the form of a striking plate adapted to be moved relatively to the arm 30 to apply pressure to a die placed upon a piece of sheet material on the cutting bed 18. To secure the supporting arm 30 firmly to the casting 16, the upper portion of the arm is provided with laterally and oppositely extending flanges 32 held in abutting relation to similarly arranged flanges 34 on the casting 16 by means of screw bolts 36. Similarly, the lower portion of the supporting arm 30 is provided with laterally and oppositely extending flanges 38 held in abutting relation to similarly arranged flanges 40 on the casting 16 by screw bolts 42. It will be noted that the arm 30, by reason of its attachment to the casting 16, may be rotated in a horizontal plane substantially parallel to the top face of the cutting bed 18, but that it is immovable in a vertical direction. The horizontal movement of the arm 30 serves to position the presser member 31 over the cutting die on any portion of the top of the cutting bed prior to the initiation of the power operation of the machine during which a vertical reciprocation is imparted to the presser member with relation to its supporting arm 30.

In order to reciprocate the presser member 31 in a substantially vertical direction relatively to the arm 30, to cause the presser member 31 to apply pressure to the die and immediately thereafter to be moved into inoperative position, power-actuated mechanism supported in the arm 30

is provided. As illustrated best in Fig. 2, the arm 30 carries in suitable bearings three parallel shafts 44, 46 and 48, equally spaced apart and extending transversely to the longitudinal direction of the arm 30. The three shafts 44, 46, 48 serve as pivotal connections between the upper ends of a series of toggles (Fig. 1) and the arm 30. The lower ends of the toggles are pivotally secured to the presser member 31, the latter thus being supported by the toggles. In the illustrated form of the invention, there are provided six toggles which will now be described. Secured on the left-hand portion of the shaft 44, as viewed from the front of the machine, is the upper end of a toggle link 50 pivotally connected at its lower end to a toggle link 52 (Fig. 1), the lower end of the latter being pivotally secured to a boss provided at the top face of the presser member 31. Similarly, a toggle link 56 is secured at its upper end on the right-hand portion of the shaft 44 and is connected to a toggle link 58, the lower end of which is pivotally secured to another boss provided on the presser member 31. The shaft 46 serves in a manner similar to the shaft 44 as the upper fulcrum for two toggles 60, 62 and 64, 66, connecting the shaft 46 and arm 30 with corresponding bosses on the top face of the presser member 31. Finally, the shaft 48 is connected to corresponding bosses on the presser member 31 by means of similarly arranged toggles 68, 70 and 72, 74. In the broken positions of the six toggles, as illustrated in Fig. 1 of the drawings, the presser member 31 is maintained in its elevated inoperative position and, upon movement of the toggles into the extended positions by mechanism which will be presently described, the presser member 31 is moved downwardly with relation to the supporting arm 30 to apply pressure to the die placed upon the work resting on the cutting bed 18. For the purpose of causing the presser member 31 to move in a substantially rectilinear path during its up and down movements, a link 75 (Figs. 1 and 3) is pivotally mounted at one end on the pivot pin that connects the toggle link 70 to the corresponding boss on the presser member 31, and at its other end to a boss provided in the supporting arm 30. The length of the link 75 is sufficient to ensure a substantially straight vertical reciprocation of the presser member 31, although strictly speaking the end of the link 75 pivotally connected to the presser member 31 moves in an arc during the vertical reciprocation of the presser member, it being understood, however, that the extent of the vertical movements of the presser member is only relatively small.

To actuate the toggles and thereby to reciprocate the presser member 31, the center joints of all toggles 50, 52 and 60, 62 and 68, 70 located at the left-hand side of the arm 30, as seen from the front of the machine, are connected by a horizontal bar 76, and similarly, the center joints of all toggles 56, 58 and 64, 66 and 72, 74 located at the right-hand side of the arm 30 are connected by a horizontal bar 78 (Fig. 2). The left-hand extremities of both bars 76 and 78 are pivotally secured by pins 79 to a yoke-shaped link 80 pivotally connected at 81 (Figs. 1 and 2) to an upwardly extending arm of a bell crank lever 82 mounted to rock about a shaft 84 secured in the arm 30. Counter-clockwise rotation of the bell crank lever 82, as viewed in Fig. 1, causes a displacement of the bars 76, 78 toward the left of Fig. 2 with the result that the toggles are moved into their extended positions and the presser

member 31 moved downwardly to apply pressure to the die.

To hold the above-described toggles in their broken positions with the presser member 31 in its elevated inoperative position, the toggle link 56 has an upwardly extending portion 86 (Fig. 1) connected by a spring 88 to the above mentioned upwardly extending arm of the bell crank lever 82.

To rotate the bell crank lever 82 in a counter-clockwise direction, as viewed in Fig. 1, the following mechanism is provided. The substantially horizontally extending arm of the bell crank lever is cup-shaped and provided with a central bore. Seated in the cup-shaped portion of this arm is a semi-spherical member 90, secured to a rod 92 extending downwardly through the central bore in the horizontal arm of the bell crank lever. The rod 92 is disposed in alignment with the axis of rotation of the casting 16 and the supporting arm 30. Up and down movements are imparted to the rod 92 by a crank pin 94 surrounded by a strap to which the lower end of the rod 92 is secured. The crank pin 94 is provided at the right-hand extremity of a horizontal shaft 96 (Fig. 1) mounted in bearings in the lower portion of the frame 10 and rotated by means of a one-revolution clutch 98 connected with a pulley or flywheel 100. It will be noted that part of the presser-actuating mechanism, in particular the shaft 96, is immovable as a unit in view of its mounting in the frame 10, and that another part of that mechanism, in particular the above-described toggles, the bell crank lever 82 and the bars 76, 78, is mounted in the arm 30 and, hence, participates in the swinging movements of the arm 30. Accordingly, by mounting the rod 92 which may be regarded as the connecting element between the stationary and movable parts of the presser-actuating mechanism, in alignment with the axis of rotation of the arm 30, the swinging movements of the arm 30 do not interfere with the operation of the presser-actuating mechanism, so that the latter mechanism may be rendered effective to operate the presser member 31 in any angular position of the arm 30.

In order to trip the clutch 98 and thereby initiate the operation of the presser member 31, the arm 30 is provided at its front end with a vertically movable handle 102 (Fig. 1) engaged by a trip lever 104 mounted to swing about a pivot pin 106 secured in the arm 30. The left-hand end of the lever 104 is provided with a recess 105 in which is seated the lower end of a vertically extending rod 108, disposed in alignment with the axis of rotation of the casting 16 and the arm 30, as well as with the rod 92. The rod 108 is guided for vertical movement in a bore provided in the upper extension of the casting 16 and its upper end engages a floating link 110 provided with two slots illustrated in Fig. 1. The slots are engaged by rollers 112 and 114 rotatably mounted on the frame 10. The link 110 is connected by means of a bar 116 to a clutch tripping member 118. As will be seen, upon downward movement of the handle 102 by the operator the lever 104 is rotated in a clockwise direction, as viewed in Fig. 1, to impart an upward movement to the rod 108 which in turn causes the link 110 and the bar 116 to impart a clutch tripping movement to the member 118. Engagement of the clutch 98 causes the shaft 96 to make a single complete revolution as a result of which the presser member 31 is reciprocated vertically to apply pressure to the die and to move back into

its inoperative position. Moreover, it will be noted that one part of the above-described mechanism for initiating the power operation of the machine is mounted on the horizontally movable arm 30 and another part on the frame 10, the rod 108 serving as the connecting element between the part mounted on the arm and the part mounted on the frame. Owing to the fact that the rod 108 is disposed in alignment with the axis of rotation of the arm 30, the clutch may be easily tripped by a downward movement of the handle 102 in any angular position of the arm 30 since the leverage effect on the part of the connections between the handle 102 and the clutch 98 always remains the same. This is contrary to commonly used structures in which the leverage effect is reduced the more the presser arm or its equivalent member is swung laterally away from its normal forwardly extending position.

Inasmuch as the arm 30 is immovable vertically, the reactive forces resulting from the application of pressure by the presser member 31 to the die on the cutting bed 18 are necessarily absorbed by the arm 30. To increase the strength of the arm 30 and its capacity to absorb these reactive forces, the arm 30 is preferably reinforced by struts, as illustrated in Fig. 1. To this end, the above-mentioned collar 24, surrounding the upper extension 13 of the casting 16, is provided with two bosses 120 into which are threaded tubular rods 122 and 124 (Figs. 1 and 3), the lower ends of which are secured in bosses 126, 128 provided at the top of the arm 30. Obviously, the tubular rods 122 and 124 serve to counteract any tendency to deflect the forward end of the arm 30 upwardly.

In order to strengthen the arm 30 also to counteract any tendency to deflect it downwardly, the casting 16 is provided with bosses 130 (Figs. 1 and 2) into which are threaded the lower extremities of rods 132 and 134. The rods converge at their upper ends (Fig. 2) and merge into a single bar 136 conveniently secured to the above-mentioned shaft 46.

In the operation of the illustrated machine, the operator grasps the handle 102 and swings the arm 30 horizontally to position the presser member 31 supported thereon over a die previously placed upon the sheet material located on the cutting bed 18. Upon downward movement of the handle 102, the above-described mechanism for initiating the power-operation of the machine is operated to trip the clutch 98 and thereby to impart a single revolution to the shaft 96, as a result of which the toggles connecting the presser member 31 to the supporting arm 30 are moved into their extended positions and then back again and the presser member 31 itself is caused to strike upon the die so as to cut out a blank from the sheet material. Thereupon, the presser member 31 is immediately withdrawn under the power-operation of the shaft 96. The clutch 98 automatically disconnects the shaft 96 from the pulley 100 after one revolution of the shaft with the toggles again assuming their broken positions, in which they are held by the spring 88.

Having described my invention, what I claim as new and desire to secure by Letters Patent of the United States is:

1. A clicking machine, having in combination a frame, a cutting bed, a casting mounted in the frame for angular motion about a vertical axis, an arm secured to the casting, a presser member carried by the arm and arranged for vertical movement relatively to the arm to apply pressure to a die placed on a piece of sheet material on the cutting bed, a toggle mechanism for actuating the presser member, power means for actuating the toggle mechanism, and means for initiating the operation of the power means, one part of the initiating means being disposed in alignment with said vertical axis.
2. A clicking machine, having a cutting bed, a support constrained to move substantially parallel to the cutting bed about a vertical axis, a presser member movable relatively to the support to apply pressure to a die placed on a piece of sheet material on the cutting bed, a toggle for operating the presser member, yielding means for holding the toggle in a broken position and thereby to hold the presser member in its inoperative position, and means for moving the toggle into extended position to impart an operative movement to the presser member.
3. A clicking machine, having in combination a frame, a cutting bed, an arm mounted in the frame for angular movement about a substantially vertical axis, a presser member carried by the arm and arranged for vertical movement relatively to the arm toward and away from the cutting bed, a plurality of toggles mounted upon the arm and operable to actuate the presser member, a member connected to the toggles for operating the same, a bell crank lever fulcrumed in the arm and pivotally connected to the toggle operating member, and a power-actuated connecting rod disposed along said vertical axis for swinging the bell crank, thereby to effect operation of the toggles.
4. A clicking machine, having a frame, a cutting bed mounted on the frame, an arm mounted on the frame for movement across the bed angularly about a vertical axis only, a presser member mounted upon the arm for movement relatively to the arm toward and from the bed, power means for positively moving the presser member toward and away from the bed, a clutch for connecting said power means operatively with the presser member, clutch tripping means carried by the arm, and connections between the clutch and clutch tripping means disposed substantially in alignment with said vertical axis.
5. A clicking machine, having a frame, a cutting bed mounted on the frame, an arm mounted on the frame for movement across the bed angularly about a vertical axis, a presser member mounted upon the arm for movement relatively thereto toward and from the bed, a series of toggles mounted on the arm for operating the presser, a common toggle operating member, a bell crank lever mounted on the arm and connected to the toggle operating member, power means including a crank for rocking the bell crank lever to operate the toggles, and a link having at one end a ball and socket joint connection with the bell crank lever and being connected at its other end with the crank.

MILTON H. BALLARD.
